CLAIM

We claim the ornamental design for a laptop-type computer, as shown and described.

DESCRIPTION

FIG. 1 is a top, front, right perspective view of the claimed design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The ornamental design which is claimed is shown in solid lines in the drawings. Broken lines formed by equal length dashes show unclaimed portions of the design. While the dash-dot-dash lines show boundaries between the claimed and unclaimed portions of the design. The pairs of closely adjacent, spaced jagged broken lines form no part of the claimed design and the portions between such pairs of
